UNITED STATES PATENT OFFICE.

DENNIS C. FAUSS, OF NEW YORK, N. Y.

DESIGN FOR A BADGE.

SPECIFICATION forming part of Design No. 32,845, dated June 19, 1900:

Application filed May 16, 1900. Serial No. 16,935. Term of patent 7 years.

To all whom it may concern:

Be it known that I, DENNIS C. FAUSS, a citizen of the United States, and a resident of the city of New York, borough of Brooklyn, in 5 the county of Kings and State of New York, have invented and produced a new and original Design for a Badge, of which the following is a full, clear, and exact description.

Reference is to be had to the accompanying 10 drawing, forming a part of this specification, in which the figure is a face view of a badge, showing the new design.

The leading feature of my new design for 15 a badge consists in a diamond-shaped body portion in which is a monogram, the portions of the monogram adjacent to the edges of the body portion being parallel therewith, so that

the outer marginal lines present a general diamond shape. The surface of the body portion has a frosted appearance, and the 20 monogram is represented in solid color.

Having thus described my invention, I claim as new and desire to secure by Letters Patent—

The design for a badge, as herein shown 25 and described.

In testimony whereof I have signed my name to this specification in the presence of two subscribing witnesses.

DENNIS C. FAUSS.

Witnesses:
